(57) **CLAIM**

The ornamental design for a biometric door assembly, as shown and described.

DESCRIPTION

FIG. 1 is a left front perspective view of a biometric door assembly in accordance with the present invention;

FIG. 2 is a front view of the biometric door assembly of FIG. 1;

FIG. 3 is a left side view of the biometric door assembly of FIG. 1;

FIG. 4 is a right side view of the biometric door assembly of FIG. 1;

FIG. 5 is a top view of the biometric door assembly of FIG. 1; and,

FIG. 6 is a bottom view of the biometric door assembly of FIG. 1.

The broken lines in the drawings depict portions of the biometric door assembly or the environment in which the biometric door assembly is located that form no part of the claimed design.

1 Claim, 6 Drawing Sheets
